Primary Examiner — Sheryl Lane*Assistant Examiner* — Samantha N Wood(74) *Attorney, Agent, or Firm* — JCIPRNET(57) **CLAIM**

The ornamental design for an electronic percussion instrument, as shown and described.

DESCRIPTION

FIG. 1 is a perspective view of an electronic percussion instrument showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the electronic percussion instrument and form no part of the claimed design.

1 Claim, 5 Drawing Sheets(56)
